10 Claims. (Cl. 271—47)

This invention relates to sheet handling apparatus, and more particularly to apparatus selectively conditionable to advance or stop a single continuous sheet or a series of separate sheets of random varying sizes and thicknesses.

Various types of clutching arrangements have heretofore been proposed to control intermittent movement of sheets. For example, it is known to provide a continuously driven roll and an idler roll which cooperate to drive the sheet when the idler roll is biased into pinching contact with the driven roll. With such an arrangement, when the idler roll is retracted, the gap or bite between the rolls is widened to a degree where the driven roll is ineffective to advance the sheet. Since such rolls contact a relatively small area of the sheet, they must impart very high local inertia forces to the sheet. This may result in scuffing or tearing, especially of thin and flimsy sheets. Moreover, as attempts are made to provide intermittent feeding of sheets in apparatus designed to operate at the ever-increasing sheet feed rates and throughputs being sought in data processing machines, this problem of inertia forces and loads becomes so critical that roll-type clutching arrangements prove unsatisfactory. Furthermore, these roll-type arrangements are not practical for handling short sheets because the distance between rolls must be less than the length of the short sheet in order to maintain positive control over sheet movement; and if the rolls are spaced so closely along the feed path as to maintain such positive control, the sheet handling apparatus will become correspondingly more expensive because of the relatively high cost of such rolls.

One object of this invention is therefore to provide a sheet handling apparatus which is relatively inexpensive and yet is capable of handling sheets of random varying sizes and thicknesses, including very small and short sheets.

Another object is to provide a relatively inexpensive apparatus selectively operable to drive sheets positively or positively brake sheets against movement, so that such sheets may be fed intermittently and yet always under positive control.

Another object is to provide a sheet handling apparatus which is capable of stopping a sheet while it is traveling at high speed and is capable of restarting a sheet with a minimum of inertia corresponding substantially only to that of the sheet itself.

Still another object is to provide a sheet handling apparatus wherein the sheet may be advanced selectively at any one of a plurality of speeds.

According to these objects, the sheet handling apparatus herein illustrated and embodying the invention comprises a pair of transversely spaced convexly curved longitudinally extending brake shoes preferably protruding from a convexly curved stationary guide plate. A plurality of belts, preferably having guided contact with said plate, normally move at different speeds in closed paths. These paths preferably lie between the transversely spaced brake shoes. A separate flexible driving control band is superposed over each belt; and a flexible brake band is superposed over each brake shoe. This defines a longitudinally extending sheet receiving guideway under the bands and generally following the convex contour of the plate.

Means are provided to tighten the brake bands and loosen the driving bands to prevent movement of sheets through the guideway. This means is also operable to

2

tighten a particular selectable one of the driving bands and concurrently loosen the brake bands to cause sheets to be advanced through the guideway at substantially the peripheral speed of the belt contacted by the tightened band.

The foregoing and other objects, features and advantages of the invention will be apparent from the following more particular description of a preferred embodiment of the invention, as illustrated in the accompanying drawings, wherein:

FIG. 1 is a side elevation view of a sheet handling apparatus embodying the invention;

FIG. 2 is a plan view of the apparatus;

FIG. 3 is a section view taken along the line 3—3 of FIG. 1;

FIG. 4 is an end view, partly broken away, taken from the right end of FIG. 2;

FIG. 5 is an exploded view of the band control portion of the apparatus; and

FIG. 6 is a schematic diagram of an electrical circuit which may be used in the apparatus.

Description

As illustrated in FIGS. 1 to 3, the sheet handling apparatus embodying the invention comprises a guide plate 10 providing a convexly curved surface 11. A plurality of driving belts, such as 12, 13, ride over the surface 11. The surface 11 and also the inner surfaces of belts 12, 13 are formed of materials having a low coefficient of friction to minimize wear. A pair of laterally spaced braking strips or brake shoes 14, 15 straddle the driving belts 12, 13 and are secured to the plate surface 11 such as by cement. These brake shoes and the outer surfaces of the driving belts are formed of materials having a higher coefficient of friction sufficient to frictionally grip all sheets to be handled, irrespective of random variations in their frictional characteristics.

Bands 16, 17, 18, 19 are superposed over the outer surfaces of the belts 12, 13 and the brake shoe 14, 15, respectively, to define a plurality of longitudinally extending, convexly curved, laterally spaced guide channels therebetween. These channels, in combination, provide a guideway 20 that is under the bands and adapted to receive sheets S, such as bank checks, tabulating cards, letters or the like. These bands preferably are formed of polished steel having a very low coefficient of friction.

Each driving belt 12 and 13 passes around a respective set of identical idler rolls 21, 22 disposed beyond the opposite ends of plate 10. Rolls 21 are laterally spaced and rotatably mounted on a common stud 23, whereas rolls 22 are similarly spaced and mounted on a common stud 24. A driven roll 25 drives belt 12 at a preselected lineal speed which is slower than the lineal speed at which a driven roll 26 drives belt 13. As illustrated, this is accomplished by driving the rolls 25, 26 from the same shaft 27, and simply making the diameter of the slower speed roll 25 the appropriate degree less than that of roll 26.

A separate tensioning mechanism 28 is provided for keeping each driving belt 12, 13 tensioned. Each such mechanism may comprise a lever 29 which is fulcrumed on a common stud 30 and carries a roll 31 at one end. A separate spring 32 acts on each lever to bias the roll 31 against the respective belt 12 or 13 to maintain a pre-selected tensioning force thereon.

The bands 16 to 19 have their respective one ends suitably secured, such as by screws 33a, to a common anchor member 33; and their opposite ends are secured, as by screws 34a, to a common anchor member 34. These members 33 and 34, in turn, are suitably secured to and supported by a fixed back plate 35. The studs 23, 24, 30 are also secured to back plate 35; and shaft 27 passes rearwardly through the back plate and is driven by suitable means (not shown). Spacers and/or bearings, such

as 36, 37, 38, 39, are employed to provide a requisite spacing of the components from the back plate 35.

For controlling positioning of the respective bands 16, 17, 18, 19, there are provided separate electro-magnets 40, 41, 42, 43. As best shown in FIG. 5, four bell cranks 44, 45, 46, 47 are rockably mounted on a common stud 48. This stud passes through aligned bores through transversely spaced lugs, like 34b, projecting from anchor member 34. Laterally secured to the respective upper arms of each of these bell cranks 44, 45, 46, 47 are armatures 44a, 45a, 46a, 47a that are attractable to the cores of the respective magnets 40, 41, 42, 43.

Whenever any bell crank 44 to 47 is rocked counter-clockwise about stud 48, its lower arm will press down on the corresponding band 16 to 19. This will correspondingly tighten that band and hence reduce the clearance between that band and the associated belt 12, 13 or brake shoe 14, 15. As best shown in FIG. 5, the bell cranks 44, 45 are associated with the driving magnets 40, 41, respectively, and are biased clockwise about stud 48 by helical springs 44b, 45b, respectively. Thus, when magnets 40, 41 are deenergized, the bell cranks 44, 45 will exert no tightening force on the bands 16, 17. On the other hand, the bell cranks 46, 47 (which are associated with the brake magnets 42, 43, respectively) are biased counter-clockwise about stud 48 by helical springs 46b, 47b, respectively. Thus, when magnets 42, 43 are de-energized, the bell cranks 46, 47 will apply a tightening force to the brake bands 18, 19, respectively. The bands will thus press all sheets then in the guideway 20 against the high friction brake shoes 14, 15 with sufficient force to clamp the sheets and stop their movement. This desirably provides a "fail safe" feature, whereby sheet movement will be prevented in event of failure of power supply to the magnets.

Power to the magnets may be supplied via any suitable circuitry, including electronically controlled circuitry. As shown in FIG. 6, for purposes of simplified illustration, this circuitry may comprise a manually operable switch 52. With switch 52 in a high-speed feed or drive position H, a circuit will be completed from a source of power, such as a battery 53, through the high speed driving magnet 41 and the brake magnets 42, 43 in series and a suitable resistor 54 back to the source. With switch 52 in a low speed or drive position L, the circuit will be completed from the battery 53 through the magnets 40, 42, 43 in series, and back to the battery, in bypass of the magnet 41. Thus, magnets 40, 41 will be energized selectively; and whenever either is energized, both brake magnets 42, 43 will be energized. However, when switch 52 is moved to a braking position B, the circuits will be opened to cause de-energization of all magnets 40 to 43.

Operation

Assume initially that the switch 52 is in braking position B (FIG. 6), in which all magnets 40 to 43 are de-energized; and that rolls 25, 26 are being driven by shaft 27.

Under these conditions, the various components will be in the respective positions in which they are shown in the drawings. The driving belts 12, 13 will be moving at preselected low and high speeds, respectively; but the associated flexible driving bands 16, 17 will lie loosely over the belts because the bell cranks 44, 45 will be rocked to their ineffective positions by springs 44b, 45b. Hence, no sheet driving frictional force will be applied by the belts 12, 13 to any sheets S which may then be in the guideway 20. However, the brake bands 18, 19 will be forced against the corresponding brake shoes 14, 15 by the bell cranks 46, 47 due to the bias forces exerted by the springs 46b, 47b, respectively. Thus, any sheets S in the guideway 20 will be firmly pinched between the brake bands and brake shoes and positively be prevented from moving. Thus, under the assumed condition, no sheets will be fed through the guideway 20.

To feed sheets through the guideway 20 at a low speed, switch 52 is moved to position L, in which magnets 40, 42, 43 are concurrently energized and magnet 41 is de-energized. With magnets 42, 43 energized, the armatures 46a, 47a will be attracted and cause the lower arms of the bell cranks 46, 47 to be rocked out of effective impinging contact with the brake bands 18, 19. This will relieve the braking force heretofore applied to the sheets. Meanwhile, with magnet 40 energized, armature 44a will be attracted for forcing the lower arm of bell crank 44 down against the corresponding drive band 16. When the band 16 is thus tightened against belt 12, all sheets S will be driven through the guideway 20 at a speed corresponding to the relatively low preselected peripheral speed of said belt.

To feed sheets S at a higher speed, switch 52 is moved to position H, in which the magnets 41, 42, 43 are concurrently energized and magnet 40 is de-energized. The brake bands 18, 19 will be loosened, as during low-speed operation. However, band 17 (instead of band 16) will be forced down against the corresponding driving belt 13 due to attraction of bell crank 45 by the energized magnet 41. Hence, sheets S will now be driven through the guideway 20 at a speed corresponding to the relatively high preselected peripheral speed of belt 13.

It is to be noted that, when tightened, the driving band 16 or 17 exerts a force on the sheets S sufficient to maintain them in contact with the corresponding driving belt 12 or 13. However, the pressure exerted on the sheets by these driving bands is not great enough to bind the sheets. Thus, when the brake bands 18, 19 and either driving band 16 or 17 are relaxed, the low friction surface of the bands permits sheets to move freely through the guideway 20 under the control of any driving band 16 or 17 which may then be tightened.

If preferred, a single brake magnet may be used in lieu of the separate brake magnets 42, 43. In such event, a suitable cross piece would be necessary to couple the two bell cranks 46, 47 together. On the other hand, it will be apparent that a single brake magnet, single brake shoe and single brake band may be used. Similarly, the number of driving belts may be increased, and groups of two or more such belts could be driven at the same speed. Moreover, instead of training the driving belts 12, 13 over the curved guide plate 10, those belts could be guided over idler rolls, or over idler rolls which extend up through cut-outs in the plate 10.

It should also be noted that the bands 16 to 19 need not be anchored at both ends to stationary members like 33, 34. The bands could be anchored at their respective one ends to a stationary member, like 34, and at their respective other ends be secured to an oscillatable member. In such case, the brake bands 18, 19 would be connected to one part of the periphery of the oscillatable member, and a single driving band, such as 17, would be connected to another, preferably opposite part of the periphery of said member. Thus, when the oscillatable member is oscillated a slight degree one way, all brake bands will be tightened and the driving band will automatically and concurrently be loosened; and when such member is oscillated the other way, the brake bands will be loosened and the driving band will be concurrently tightened. With such an arrangement, multiple driving bands should be used only if they are driven at the same peripheral speeds.

Finally, it is to be noted that the apparatus embodying the invention may be used to control movement of a continuous sheet or web (such as tape or transversely perforated continuous paper forms, etc.), as well as of a series of separate or individual forms of random varying sizes and thicknesses. Accordingly, the term "sheet" as used in the claims is intended generically to cover both separate sheets and a continuous sheet or web.

While the invention has been particularly shown and described with reference to a preferred embodiment thereof, it will be understood by those skilled in the art

that the foregoing and other changes in form and details may be made therein without departing from the spirit and scope of the invention.

What is claimed is:

1. Sheet handling apparatus comprising
a belt and a band providing a longitudinally extending guideway through which at least one sheet is advanceable, 5
one means having two discrete positions, one for tightening the band against the belt and the other for loosening the band from the belt, 10
means for moving the belt to cause each sheet to be advanced thereby while said band is tightened, and control means responsive to a first and a second of two discrete control conditions to actuate said one means to its said one position and other position, respectively, whereby the belt will be rendered substantially ineffective to drive such sheet while the one means is in its said other position. 15
2. Sheet handling apparatus comprising
a plurality of endless elements arranged side by side and having portions which are constrained to move in substantially similar laterally adjacent paths, 20
a band-like member normally loosely superposed on each such portion to define a longitudinally extending sheet-receiving guideway between said portions and members, 25
means for driving each endless element at a different peripheral speed, and
means for selectively tightening the members against said elements to cause a sheet to be advanced through the guideway at substantially the peripheral speed of that particular endless element against which the associated member is tightened. 30
3. Sheet handling apparatus comprising
endless means constrained to move in a non-circular path, 35
a member extending along an elongated portion of the path adjacent the periphery of said endless means to define between said endless means and member a longitudinally extending sheet-receiving guideway, and
means operable selectively to one or the other of two preselected positions to tighten said member against said endless means to cause driving of a sheet or loosen said member therefrom to render said endless means substantially ineffective to drive a sheet, 40
whereby when the last-named means is tightened, a sheet will be pinched along a substantial portion of its length between said member and endless means and cause the sheet to be advanced through said guideway at a speed corresponding substantially to the peripheral speed of said endless means. 45
4. Sheet handling apparatus comprising
means defining a guideway for guiding at least one sheet along a predetermined longitudinally extending path, 50
said means including
a longitudinally extending member and a flexible strip-like member having superposed portions to provide said guideway therebetween, 60
means for anchoring one end of said flexible member, control means to selectively tighten said flexible member against said longitudinally extending member or loosen it therefrom to correspondingly vary the clearance between said members along substantially the entire length of the guideway, and
means for moving the longitudinally extending member to cause each sheet to be advanced through the guideway provided the control means is conditioned to tighten said flexible member. 65
5. Sheet handling apparatus comprising
means providing a plurality of generally laterally spaced longitudinally extending guideways through which at least one sheet is advanceable, and including 70

a belt and a band cooperating to provide at least part of one of said guideways, and
stationary brake shoe means and movable brake band means cooperating to provide at least part of another of the guideways;
means for tightening the band against the belt; means for tightening the brake band means against said stationary means to arrest sheet movement; and means for moving the belt to cause each such sheet to be advanced through the guideways when the band is tightened against said belt provided said brake band means is not tightened.

6. Sheet handling apparatus comprising
endless sheet-driving means movable in a predetermined closed path,
a member cooperating with a portion of the periphery of said endless means to define therebetween one longitudinally extending sheet-receiving guideway, 20
brake band means and brake shoe means for defining therebetween another longitudinally extending sheet-receiving guideway laterally adjacent said one guideway, and
means for controlling movement of said member and brake band means relative to said endless means and shoe means, respectively, and operable under one condition to loosen said brake band means and concurrently tighten said member against said endless means to cause a sheet to be moved at the peripheral speed of said endless means, and operable under another condition to loosen said member from said endless means and concurrently tighten said brake band means against said shoe means positively to arrest movement of the sheet through said guideways.
7. Sheet handling apparatus comprising
a plurality of belts arranged side by side, 25
a corresponding plurality of bands each having a portion superposed on a respective belt to define a guideway
means for selectively controlling the clearance between the respective bands and their corresponding belts, and
means for driving at least some of the belts at different speeds to cause a sheet to be driven through the guideway at the peripheral speed of that particular belt having a minimum clearance with its corresponding band.
8. Sheet handling apparatus comprising
means providing two generally laterally spaced longitudinally extending guideways through which sheets are advanceable, and including
a belt and a band cooperating to provide at least part of one of said guideways, and
stationary means and brake band means cooperating to provide at least part of the other guideway; control means operable under one condition to cause tightening of the band against the belt and concurrent loosening of the brake band means, and operable under another condition to cause loosening of the band from the belt and concurrent tightening of the brake band means against stationary means; and means for moving the belt to cause a sheet to be advanced through the guideways provided said control means is in its said one condition.
9. Sheet handling apparatus comprising
a pair of laterally spaced longitudinally extending stationary brake shoes, 30
at least one driving belt disposed laterally between said shoes,
a respective band superposed over adjacent convex portions of each shoe and belt to define a guideway
means anchoring the respective one ends of each band, means for normally holding certain of the bands against the brake shoes to arrest movement of a sheet through the guideway,

one means operable to release the certain bands from the brake shoes to permit sheet movement, and another means operable to tighten another of the bands against the belt to cause the sheet to be driven at the peripheral speed of the belt, whereby sheet movement will be prevented if said one and other means fail to operate.

10. The combination according to claim 9, wherein the means normally holding the certain bands against the brake shoes are resilient means, and wherein said one means and other means are electromagnetically controlled, the said one means being energizable to release said certain bands, and said other means being energizable to tighten said other band, and including means for effecting concurrent energization of said one and other means.
